LOOSE LEAF BINDER

Filed June 13, 1928

INVENTOR.

Lewis Barnes.

BY *Thomas J. Donnelly*
ATTORNEY

UNITED STATES PATENT OFFICE

LEWIS BARNES, OF FARMINGTON, MICHIGAN

LOOSE-LEAF BINDER

Application filed June 13, 1928. Serial No. 284,951.

My invention relates to a new and useful improvement in a loose leaf binder adapted for mounting in a cover upon a suitable support and affording means for securing leaves or pages bound together in a condition so that they may be readily removable.

It is an object of the present invention to provide a device of this class which will be simple in structure, economical of manufacture and highly efficient in use.

Another object of the invention is the provision of a binder which will be securely locked when in closed position and which may be easily and quickly moved to open position.

Another object of the invention is the provision of a binder which may be mounted on a suitable support and moved to various positions.

Other objects will appear hereinafter.

The invention consists in the combination and arrangement of parts hereinafter described and claimed.

The invention will be best understood by a reference to the accompanying drawings which form a part of this specification and in which,

Fig. 1 is a perspective view of the invention.

Fig. 2 is a transverse sectional view of the invention.

Fig. 3 is a view taken on line 3—3 of Fig. 2.

Fig. 4 is a perspective view of the binder in unassembled relation.

Fig. 5 is a view similar to Fig. 4 of a modified form of the invention.

Fig. 6 is a transverse sectional view of the modified form of the invention.

In the invention I have illustrated a bar 9 which is provided with openings 10 through which fastening means may be projected for securing the bar 9 to a cover or other suitable support. A plate 11, preferably formed from sheet metal, is provided with the doubled over end 12, a notch 13 being cut out of the plate 11 and the doubled over portion 12 at the juncture of these two parts. At the opposite end of the plate 11 tongues 14 are bent out. At the forward end of the plate 11 there is provided an upwardly offset or

raised portion 15 in which is formed an opening 16, the rear side of this opening being straight as appears in Fig. 4. Punched from the plate 11 and extended downwardly are tongues 17, behind which and against which is adapted to engage the end 18 of a Z-shaped spring, the opposite end 19 being positioned in a slot 20 formed in the end of the binder hook 21. After engagement of the end 19 in this slot the prongs at opposite sides of the slot are clinched so that the member 19 is securely fastened in the slot 20, while at the same time, the hook 21 is free for pivotal movement, on the member 19 as an axis. Formed in the inner side of the forward or free end of the hook 21 is a notch 22 adapted, when the hook is moved to closed position, for receiving the straight edge of the upset portion 15. When mounted on the bar 9 the portion 12 is doubled over so as to clamp the bar 9 against the plate 11 and the tongues 14 are angularly turned for serving the same purpose as appears in Fig. 2. If desired, these parts 12 and 14 may be so pressed against the bar 9 as to secure the hook in fixed relation on the bar 9 or they may be loosely bent to permit slidable movement so that the location of the hooks on the bar 9 may be varied.

In use, when it is desired to place leaves in the binder the hook may be moved to the dotted closed position shown in Fig. 2, this forward movement of the hook bodily being permitted by the size of the opening 16 and the size of the notch 19 and the resiliency of the Z-shaped spring, the portion 19 being moved bodily to approach the portion 18. When moved to this position the hook may be swung upwardly and rearwardly on the portion 19 as a pivot into the open position shown in dotted lines in Fig. 2. When moving the device to closed position a pressing downwardly will effect a forward movement of the part 19 sufficiently to permit the end of the hook 21 to enter the upset portion 15, the resiliency of the Z-shaped spring being sufficient to move the free end of this hook rearwardly so as to permit the rear or straight edge of the upset portion 15 to engage in the notch 22. This spring is sufficiently

strong to normally retain these parts in locked relation so that undue displacement of the leaves from the binder resulting from disengagement of the hook from its locked position is reduced to a minimum.

5 In the form shown in Fig. 5 I have indicated the bar 9' which is equivalent to the bar 9, as formed integral with the plate 11' which is the equivalent of the plate 11. This 10 plate 11' is provided with the tongues 17' corresponding to the tongues 17 and with the notch or slot 13' corresponding to the notch or slot 13. The portion of the plate 12' extending outwardly from the dotted line of 15 bend indicated by the numeral 27 corresponds to the portion 12, so that when these parts are folded over into the relation shown in Fig. 6, the same operation and functioning of the device is provided as explained for 20 the preferred form, the hook 21' being operated upon by the Z-shaped spring having the parts 18' and 19'.

While I have illustrated and described the preferred form of my invention, I do not wish 25 to limit myself to the precise details of structure shown, but desire to avail myself of such variations and modifications as come within the scope of the appended claims.

Having thus described my invention what 30 I claim as new and desire to secure by Letters Patent is:

1. A loose leaf binder of the class described, comprising: a yieldable axis forming member; a hook pivotally mounted by one 35 end on said axis forming member; and means for engaging the opposite end of said hook after movement of the same to a predetermined position for locking said hook in closed position.

40 2. A loose leaf binder of the class described, comprising: a hook forming member having a notch formed in one end; a yieldable axis forming member, said hook being pivotally connected at its opposite end to 45 said axis forming member; an engagement member for engaging said notch and locking said hook in closed position, said axis forming member normally tending to retain said hook in engagement with said engagement member after movement of said hook to closed 50 position, said hook being movable against the resiliency of said axis forming member for disengaging said hook from said engagement member.

55 3. A loose leaf binder of the class described, comprising: a hook forming member having a notch formed at its inner side at one end; a yieldable axis forming member, said hook being pivotally connected at its opposite end 60 to said axis forming member; an engagement member for engaging in said notch and locking said hook in closed position upon movement of said hook to closed position, said axis forming member being moved from normal position upon movement of said hook

to closed position and normally retaining said notch in engagement with said engagement member.

4. A loose leaf binder of the class described, comprising: a supporting surface, a plate 70 having a main body and one end doubled over into clamping relation with said supporting surface, said plate having a notch formed at the juncture of its main body and said doubled over end; a yieldable member extending transversely of said notch and retained in position by said doubled over end; a hook forming member engaging in said notch and pivotally connected at one end with said yieldable member; an opening formed in the main body of said plate adjacent its opposite end, the free end of said hook being engageable in said opening upon movement to closed position, the inner side of said hook having a notch formed therein for reception of the edge of said opening, said yieldable member 80 normally retaining said edge in engagement in said opening upon movement of said hook to closed position.

5. A loose leaf binder of the class described, comprising: a plate having a notch formed therein adjacent one end thereof; a yieldable member extending transversely of 90 said notch; a hook having one end bifurcated to provide a slot for reception of said yieldable member, the bifurcated end of said hook being clinched on said yieldable member for pivotally mounting said hook thereon, the opposite end of said hook having a notch formed on its inner side, said plate having an opening formed adjacent its opposite end, said hook being engageable at its free end in said opening, the rearward edge of said opening engaging in the notch in said hook, said yieldable member normally retaining 95 said edge in engagement in said notch and being sufficiently yieldable for permitting forward movement of said hook to disengaged position.

100 6. A loose leaf binder of the class described, comprising: a plate having a main body and one end doubled over and provided with a notch at the juncture of the main body and said doubled over portion; tongues punched from said main body adjacent the rearward end and extended downwardly; a yieldable member positioned between said doubled over end and said main body and extending at one end transversely of said notch and engaging adjacent its opposite end said tongues; a hook having one end slotted, said slotted end embracing said transversely extended end of 110 said yieldable member and being clinched thereon for pivotally mounting said hook thereon, the opposite end of said hook having a notch formed on its inner side; an upset portion on the forward end of said main body having an opening formed therein, said hook engaging in said opening upon movement to 115 closed position, the rear edge of said upset portion
